UNITED STATES PATENT OFFICE.

HARMON N. TRACY, OF LOS ANGELES, CALIFORNIA.

APPARATUS FOR REDUCING ORES.

1,279,180.

Specification of Letters Patent. Patented Sept. 17, 1918.

Continuation of application Serial No. 23,548, filed April 24, 1915. This application filed January 11, 1917. Serial No. 141,820.

To all whom it may concern:

Be it known that I, HARMON N. TRACY, a citizen of the United States, residing at Los Angeles, in the county of Los Angeles, State 5 of California, have invented new and useful Improvements in Apparatus for Reducing Ores, of which the following is a specification.

My invention relates to a method and apparatus for reducing ores; my object being the provision of simple, direct, and efficient method and apparatus for reducing various forms of ore, to obtain the metallic constituents thereof in metallic form. It 10 will be understood that my method and apparatus are not limited to any one particular species or class of ores; but, for the purpose of the following specification, I shall explain my method and apparatus as applied 15 to iron ores which are oxids or which may be roasted to oxids in the presence of air. This application is a continuation in part of my application S. N. 23,548, filed April 24, 1915, on apparatus for reducing ores. 20 In this application I carry on and claim those features of my former application that refer particularly to the shape, formation, etc., of the ore reducing stack; and in a co-pending application Serial No. 151,629, filed 25 30 March 1, 1917, on apparatus for reducing ores I specifically carry on and claim those matters that, in my former application, referred to combinations with the cooling chamber, etc.

It is a primary object of my invention to provide a practicable method whereby such ores may be reduced in a continuous one way flow or in a continuous stream flowing in one direction. I am aware that such ores 40 have heretofore been reduced by treatment in batches, but, to my knowledge, no simple and practicable means has yet been evolved for treating such ores continuously.

The primary features of my invention include a means for treating ores in a comparatively long and narrow vertical column by injecting a reducing fluid, say, hydrocarbon gas, into the central portions of the long and narrow column of ore. It is a particular feature of my invention that no products of combustion of a heating furnace come into contact with the column of ore, and also that atmospheric air is excluded from the treatment zone in the column by 45 50 55 60 65 70 75 80 85 90 95 100 105 110 the arrangement of the column itself; i. e.,

the column being long and narrow, the reducing gases at first displace and thereafter continuously exclude the atmospheric air, so that the reducing action is carried on in the total absence of free oxygen.

There are other features of my invention which are particularly set forth in the following specification, reference being had to the accompanying drawings, in which, for the purpose of this specification, I have 60 shown a typical and preferred form of apparatus, and in which drawings, Figure 1 is a sectional elevation showing my improved apparatus, Fig. 2 is a section taken as indicated by line 2—2 on Fig. 1, and Fig. 3 is a 65 section taken as indicated by line 3—3 of Fig. 1.

In the drawings I have shown a relatively long and narrow vertical ore stack 10, the dimensions of which may be typically as follows: height, approximately fifty to sixty feet, and internal diameter approximately thirty-three inches at the top and thirty-six inches at the bottom. The stack is made slightly larger at the bottom in order to facilitate the free passage of ore downwardly therethrough without choking. It is one of the features of my invention that the ore passes through the stack 10 under gravitational influence in such a manner that the 70 stack can be constantly kept full of ore and for this purpose I prefer to make the stack vertical, although it may extend diagonally vertically and still have the advantage of the 75 ore moving therethrough under gravitational influence. I provide a means for heating the ore which is delivered to the upper end of the stack and I prefer to heat the ore as close to the upper end of the stack as possible and to deliver the ore directly 80 into the stack with the least loss of heat.

Preferably, for this purpose I provide a revolving roasting drum 11 of any preferred design, the discharge end 11^a of the drum projecting into the upper end 10^a of the 85 stack. The drum is placed at a suitable incline so that ore fed into its upper end 11^b from the feed spout 12 will pass downwardly through the drum. A furnace or burner apparatus 13 supplies heat to the roasting 90 drum, said burner apparatus preferably being in the form shown in Fig. 1, and embodying a fluid burner 14, for gas or liquids, discharging into a conical member 15 as 95 illustrated, air being drawn into this member 100 105 110 115 120 125 130 135 140 145 150 155 160 165 170 175 180 185 190 195 198 200 205 210 215 220 225 230 around the flame, as indicated in the drawings. Control of the burner is had by valve 16 or any other suitable means. A draft stack is shown at 17 connecting with the upper end of the roasting drum 11. The spout 12 leads from any suitable bin 18 and the feed of ore is controlled by a revolving roller 19 operated by motor 20, which motor is controlled by a controller 21 on the switch board 22. This switch board 22 is mounted in a convenient position on the platform 23, said platform being preferably supported at the upper end of the stack. As hereinafter explained, the operation of my apparatus is 15 under control of a single man on the platform 23.

The drum 11 and furnace 13 not only performs the function of heating the ore directly prior to its delivery to the upper end 20 10^a of the stack 10, but also performs the function of roasting and oxidizing the ores which must preferably be changed to oxids before they are reduced in the reducing stack 10. However the ores are delivered to the 25 drum 11, it will be presumed (for the purpose of this specification) that they are delivered to the upper end of the reducing stack in the form of oxids; and the ores are discharged into the upper end of the reducing stack in highly heated condition. The 30 temperature of the ores is governed by conditions hereinafter stated.

The stack is provided at suitable intervals with cross-bars 25, forming rabblers for 35 causing the pieces of ore to move relatively to each other and to prevent the ore from settling into a solid mass in the stack. At the lower end of the stack I provide an accumulating and cooling chamber 30 of suitable 40 capacity for holding such a quantity of reduced products that cooling can be effectually carried out before the final product is taken out to atmosphere; that is, cooling below the point of oxidation. I prefer to arrange 45 the cooling means as indicated in the drawings, comprising a number of transverse tubes 31 and 31^a arranged across the cooling chamber. These tubes may be inclined upwardly toward the center as shown at 31, or 50 may extend straight across the chamber as shown at 31^a. The inclined tubes aid in the even distribution of the material over the whole chamber 30. I prefer to make at least the upper rows of tubes in this shape. At 55 one end of the tube I employ a blower fan 32 of any preferred design to provide a forced draft through the tubes; and the other ends of the tubes may communicate with a chamber 33 from which a draft stack 60 34 arises. This draft stack extends upwardly around the central reducing stack; and the hot air passing upwardly through the draft stack aids materially in keeping the reducing stack at proper temperature, forming an 65 insulation zone around the reduction stack.

The ends of the uppermost tubes 31, the ones which are at the highest temperature, may connect with a draft pipe 35 which extends upwardly and discharges into the air box 36 of furnace 13. The air thus delivered to the 70 furnace is highly heated; and I preferably supply all the air to the furnace 13 in this manner, providing a damper 37 which may be controlled by the operator on platform 23. The heat carried into the furnace by this 75 heated air is thus utilized in the heating and roasting process in the drum 11. It will be noted that, by the arrangement herein described, I return a considerable part of the 80 heat carried by the reduced products to the unreduced ores, this certain part of the heat remaining in the system and not being lost.

At the lower end of the cooling chamber 30 I place a suitable discharge conveyer 40 operated by motor 41 controlled by suitable 85 controller 42 on switch board 22. When my apparatus is in operation the attendant on the platform 23 has full control of the introduction and withdrawal of ore to and from the stack 10; and by regulating the introduction and withdrawal he may regulate the rate of flow of ore through the stack, and thus regulate the time element of the reducing action. The introduction and withdrawal are so regulated that, with the proper 90 rate of flow, the stack 10 is kept constantly full of ore which moves downwardly under the influence of gravitation at a uniform rate, moving downwardly into the reduction zone and then on downwardly out of the reduction zone into the cooling chamber below, and thence out through the conveyer 40 into any suitable conveying means or storage bins or the like.

The re-agent employed for reduction may 105 be varied to suit particular requirements; I have preferred to show and describe herein a means for introducing hydro-carbon, coal or water gas or the like to the central parts of the reduction stack 10. I may employ a 110 holder or tank 50 into which the prepared gas is passed and from which the gas is taken by a suitable compressor or blower 51 and forced through the pipe 52 to the distribution pipes 53. I may arrange a plurality 115 of sets of such pipes 53, controlled by any suitable valves 54, so that the reducing gas may be admitted to any or all of the sets. The pipes 53 extend across the stack 10 and have suitable outlets 55 on their under sides 120 so that the outlets will not be choked by the downwardly moving ore. The exact point of introduction of the gas is controlled by the proper manipulation of the valves 54, while the amount of gas supplied is regulated and controlled by controlling the compressor driving the motor 56 from the controller 57 on switch board 22. Proper pressure is maintained on the gas to cause its 125 distribution through the ore in the reducing 130

zone at the central portions of the stack. The amount of gas to be supplied must be sufficient to reduce the ore within the time period taken for the ore to pass vertically through the reduction zone. The reduction zone is that zone in which the reduction gas, spreading both upwardly and downwardly from the pipes 53, re-acts upon the ore to cause its reduction. Below the reduction zone there is a constantly downwardly moving stream of reduced metal, while above the reduction zone there is a constantly downwardly moving mass of unreduced but highly heated ore. As hereinbefore stated, the ore delivered from the roasting drum is in highly heated condition; and the operator keeps the temperature of the ore at the most efficient point, that is, at that temperature at which reduction will most efficiently take place. To enable an accurate control of the temperature I may provide pyrometers at various places in the stack, as at 60 and 61, these pyrometers having indicators 62 and 63 on switch board 22. The operator can accurately control the temperatures so as to obtain the proper temperature at and in the reduction zone; whether the total reduction action, including the breaking up of the oxids and the combination of their oxygen with the reducing agent, is exothermic or endothermic in its nature. In the one case the ore above the reduction zone is further heated by the surplus of heat arising from an exothermic action; while in the other a surplus of heat must be supplied from the furnace 13. The outward spread of the reducing gas in the relatively narrow stack drives out and displaces atmospheric air and thus excludes free oxygen entirely from the reducing zone and from the whole stack. When the apparatus is in full operation, the cooling chamber becomes filled with the gaseous products of reduction, and the metal is thus cooled in the presence of a non-oxidizing gas.

I wish to particularly emphasize that feature of my invention which includes the relatively long and narrow column of ore, and the introduction of the reducing agent at or near the longitudinal center of the column; under such conditions, as herein exemplified, that the reducing agent displaces and excludes atmospheric air so that the reaction may proceed exactly as in an air-tight chamber. I wish also to call particular attention to various subsidiary features of my method and apparatus, including the direct delivery of the heated ore to the upper end of the

reducing stack, the exclusion of all products of combustion from the reduction zone 60 and from the stack, and the control means for continuously keeping the operation of the whole apparatus at its highest efficiency.

Having described a preferred form of my invention, I claim:

1. Ore reducing apparatus, embodying a relatively long and narrow vertical stack substantially open from end to end and free from constrictions so that ore may move therethrough under gravitational action, 70 means to continuously introduce ore to the upper end of the stack, means to continuously withdraw the product from the lower end of the stack, means to control said introducing and withdrawing means so as to keep 75 the stack continuously full of ore, and means to controllably introduce a gaseous reducing agent to the ore exclusively at the middle portion of the stack, whereby a constant zone of reducing gas is maintained at the middle 80 part of the stack protected from atmosphere by the material in the stack above and below.

2. Ore reducing apparatus, embodying a relatively long and narrow vertical stack 85 substantially unobstructed and of substantially uniform diameter from end to end and free from constrictions, means for continuously introducing ore to the upper end of the stack, means for controllably continuously 90 withdrawing material from the lower end of the stack so that the stack may be kept filled with ore and material moving downwardly by gravitation, and means to introduce a fluid reducing agent to the stack and 95 ore at its middle portion.

3. The herein described method of reducing ores, embodying first continuously heating the ore, then continuously introducing the heated ore into a vertical column devoid 100 of constrictions from the top to the bottom thereof, continuously introducing a reducing agent near the central part of the column, and continuously withdrawing reduced ore at the bottom of the column, the rate of 105 introduction and withdrawal of the ore being such as to keep the column of ore constant.

In witness that I claim the foregoing I have hereunto subscribed my name this 28th 110 day of December, 1916.

H. N. TRACY.
